GRINDING MACHINE FOR SHAPING
WORKPIECES

Joseph L. Torgerson, Milwaukee, Wis.

Application October 23, 1944, Serial No. 559,876

5 Claims. (Cl. 51—92)

1

This invention relates to improvements in grinding machines.

It has particular reference to a structure especially adapted for the sharpening of the cruciform blade of a meat grinder, but many of its features are also adaptable to other grinding problems.

It is the object of the invention to provide a novel, improved and simplified form for the various adjustments and movements of a blade with respect to a grinding wheel, and to make the achievement of the requisite movements as easy and simple for the operator as is possible.

The objects will appear in more detail to those skilled in the art upon analysis of the following disclosure of the invention.

In the drawings:

Fig. 1 is a side elevation of the machine embodying the invention.

Fig. 2 is a plan view of the machine shown in Fig. 1.

Fig. 3 is an enlarged detail view in plan of the work in place upon its work support.

Fig. 4 is a side elevation of the structure shown in Fig. 3.

Fig. 5 is a detail view taken in section on the line 5—5 of Fig. 3.

Fig. 6 is a plan view of a work piece in operative relation to the grinding wheel (illustrated in broken lines).

Fig. 7 is a view fragmentarily illustrating the grinding wheel in side elevation and showing in section the blade operated on thereby, the rest of the knife assembly being indicated in broken lines in proper relation to the blade upon which the wheel is acting.

Fig. 8 is a plan view of the sharpened work piece.

Like parts are designated with the same reference characters throughout the several views.

The machine comprises a main frame at 10 provided with bearings at 11 and 12 for the shaft 13 upon which the grinding wheel 15 is supported. Pivoted from the main frame by means of a bar 16 is a subframe 17 which has oscillation in a vertical plane limited by the nut 18 adjustably threaded on a stop bolt 19 operating through a bracket 20 projecting from the main frame.

The free forward end of the subframe, from which the stop bolt 19 depends, is raised by a foot pedal 21 in the form of a lever having a connection to the subframe through the turn-buckle 22, as shown in Fig. 1. It is the purpose

2

of the subframe movement to raise and lower the work to and from the grinding wheel 15.

Mounted on the subframe 17 is a tiltable table 25 provided with ears at 26 supported on a rod 27 which extends transversely of the frame and upon which table 25 may be oscillated. It is adjustably fixed in its oscillatory position by a lever 28 extending from its forward margin and provided with a clamp screw 29 operating in a segment 30. It is the function of table 25 to determine with accuracy the angle at which the faces of the respective blades of the work pieces will be ground.

The table 25 is provided, as best shown in Figs. 4 and 5, with gib means 32, constituting a guide-way upon which the slide 33 is reciprocable to and from the main frame. Reciprocation is manually effected and controlled by a hand lever 34 pivoted to the slide at 35 and provided with a movable fulcrum at 36 upon a link 37 pivoted at 38 to the table 25 (see Figs. 2 and 3).

The cross slide 33 may be provided with an adjustable stop at 39 engageable with the gib means 32 to limit the movement of the slide toward the grinding wheel and the main frame. It is a function of this slide to reciprocate beneath the grinding wheel 15 the blade to be ground and, if desired, to bring the edge of another blade into contact with the wheel.

On the slide 33 a cup-shaped support 40 is engaged by the inverted cup-shaped work carrier 41, the coacting parts of these members being of circular cross section to permit of the indexing of the work carrier 41 with respect to its support 40. The fixtures 42 and the square plug 43 on the face of the work carrier are made to receive and position the work piece 45 which, as shown, is a cruciform article, having four blades 46 requiring grinding on the surfaces 47 and 48 (see Figs. 7 and 8).

The indexing work carrier 41 has, on its outer periphery, a number of lugs at 49 corresponding to a number of blades requiring sharpening. Surrounding the cup-shaped support 40 is a gage ring 53 provided with a handle 54 and with a clamp bolt 55 extending through the slot 56 into threaded connection with the slide 33. When the clamp bolt 55 is loosened, the handle 54 may be used to adjust the position of ring 53 to that point where its stop 57 will be engaged by the successive lugs 49 of the work carrier in position of the carrier in which the respective blades 46 of the work piece are accurately positioned for engagement by the grinding wheel.

The work piece being positioned on the fix-

tures 42 of the carrier 41, and the carrier 41 being manually indexed to engage one of its lugs 49 with the stop 57, it will be found that one of the blades of the work piece will bear properly predetermined relation to the grinding wheel 15. This relationship is predetermined, as above indicated, by the indexing of the positioning ring 53; and by the tilting of the table 25.

The sub-frame 17 is now oscillated to move the work piece upwardly, this being done by pressure of the operator's foot on the pedal 21. The exact ultimate position may be predetermined by the limit nut 18. With the subframe raised, the operator now draws the handle 34 to the right, as viewed in Fig. 3, thereby advancing slide 33 to draw one of the blades 46 beneath the grinding wheel. The operator himself will regulate the extent to which the entire length of the blade may be passed beneath the wheel. Ordinarily, more than one traverse will be made and, in the final traverse, the slide 33 may be given the extreme movement permitted by stop screw 39, thereby bringing the edge 48 of another blade into contact with the side face of the wheel 15, as shown in Fig. 6.

The surface 47 of the blade closest to the wheel and the edge 48 of the next consecutive blade of the work piece having now been ground, the operator will release pressure on the pedal 21 to allow the subframe to be lowered to the position illustrated in Fig. 1, whereupon he will manually lift the indexing work support 41 sufficiently to enable its lug 49 to clear the stop 57. He will thereupon index the support 90° to engage its next successive lug with the stop 57, thereby positioning another blade to be operated on by the wheel. The cycle of operations, as above described, is then repeated.

When the device has been properly set in the manner above set forth, it will be apparent that no skill whatever is required to achieve perfect grinding of the blades. Moreover, the grinding may be effected very rapidly, the operator's left hand controlling the lever 34, his foot controlling the pedal 21, and his right hand remaining available for indexing the work support and positioning and removing the work pieces.

I claim:

1. In a device of the character described, the combination with a frame and a tool operatively supported therefrom, of a fulcrum bar projecting laterally from the frame, a subframe pivoted on said bar and having a portion pivotally movable to and from said tool, means for actuating said portion comprising a pedal and motion transmitting connections from the pedal to said subframe, stop means adjustable between the subframe and the frame for limiting the pivotal movement of the subframe, a table, pintle means pivotally connecting the table to the subframe whereby said table is tiltable respecting said subframe, clamping means for fixing the position of tilted adjustment of the table respecting the subframe, means providing a guideway transversely of the table, a slide reciprocable upon the

guideway, handle means for reciprocating the slide, and a work carrier provided with an index mounted upon the slide.

2. The structure of claim 1, in which said handle means comprises a lever centrally in pivotal connection with the slide and having a fulcrum connection with a link, said link being pivoted to said table.

3. The structure of claim 1, in which said slide 10 is provided with a support on which the work carrier is rotatably mounted, and the work carrier is provided with a stop, said slide having an arcuately extending stop member provided with stop means for coacting with the stop of the work carrier, said member being adjustably mounted on the slide and having clamping means for maintaining its adjustment angularly about the work carrier.

4. In a device of the character described, the combination with a main frame and a grinding wheel provided with means operatively supporting it from said frame, of a subframe in pivotal connection with said frame at a point remote from said wheel, said subframe having a portion 25 adjustable to and from the wheel, means including a foot pedal and link for actuating said subframe portion toward the wheel, a stop bolt in pivotal connection with the subframe and provided with a stop nut, said frame having bracket 30 means with which said nut is engageable whereby adjustably to limit the approach of said subframe portion to said wheel, a table provided with a transverse pintle pivotally connecting the table with the subframe, a lever on the table, a segment 35 on the subframe with which said lever coacts, clamping means for adjustably securing the lever to the segment whereby adjustably to fix the tilted position of the table respecting the subframe, means providing a transverse guideway on the table, a slide reciprocable on said guideway, stop means for limiting the reciprocation of said slide respecting the table, a circular support upon the slide, a stop ring disposed upon the slide about the support, means for adjustably 40 determining the angular position of the stop ring respecting the slide, a work carrier rotatably adjustable upon the support, said ring and carrier having means interengageable in selecting indexing positions of the carrier, and fixture 45 means on the carrier for supporting a series of blades to be successively indexed into operative position beneath said wheel to be sharpened thereby, the movement of said slide carrying a selected blade longitudinally beneath the wheel 50 at an angle determined by the tilt of the table and a level determined by said stop nut and bracket when said subframe portion is elevated by said pedal.

5. The device of claim 4, in further combination with slide actuating means comprising a link pivoted to the table, and a hand lever fulcrumed to the link and provided with a pivotal connection to the slide.

JOSEPH L. TORGERSON.
